US00D782435S

(12) **United States Design Patent** (10) **Patent No.:** **US D782,435 S**
(45) **Date of Patent:** **** Mar. 28, 2017**

(54) **MOBILE PHONE**

(71) Applicant: **Huawei Device Co., LTD**, Shenzhen (CN)

(72) Inventors: **Jue Yuan**, Shanghai (CN); **Jiaxi Wang**, Shanghai (CN); **Qingmeng Li**, Shanghai (CN); **Yanxin Dai**, Shanghai (CN)

(73) Assignee: **Huawei Device Co., LTD** (CN)

(**) Term: **14 Years**

(21) Appl. No.: **29/493,383**

(22) Filed: **Jun. 9, 2014**

(30) **Foreign Application Priority Data**

Dec. 9, 2013 (CN) 2013 3 0609345

(51) **LOC (10) Cl.** **14-03**

(52) **U.S. Cl.**

USPC ..... **D14/138 AA**; D14/138 C; D14/138 G

(58) **Field of Classification Search**

(57) **CLAIM**

The ornamental design for a mobile phone, as shown and described.

DESCRIPTION

FIG. 1 is a bottom view of a mobile phone;

FIG. 2 is a top view thereof;

FIG. 3 is a right side view thereof;

FIG. 4 is a front view thereof;

FIG. 5 is a left side view thereof;

FIG. 6 is a back view thereof; and,

FIG. 7 is a front perspective view thereof.

The broken line portion of the figure drawings is included to show unclaimed subject matter only and forms no part of the claimed design. The oblique line shading shown in FIGS. 4 and 7 represents a glass surface.

1 Claim, 6 Drawing Sheets
